Attorney

UNITED STATES PATENT OFFICE.

CARL W. CARLSON, OF GALVA, ILLINOIS.

DISPLAY-RACK.

1,217,409.

Specification of Letters Patent. Patented Feb. 27, 1917.

Application filed May 15, 1916. Serial No. 97,690.

To all whom it may concern:

Be it known that I, CARL W. CARLSON, a citizen of the United States, residing at Galva, in the county of Henry and State of Illinois, have invented certain new and useful Improvements in Display-Racks; and I do declare the following to be a full, clear, and exact description of the invention, such as will enable others skilled in the art to 13 which it appertains to make and use the same.

This invention relates to new and useful improvements in display racks of that character which are intended for exhibiting 15 samples of merchandise on sale.

The principal object of the invention is to provide a device of this character which while simple in construction, will exhibit articles in a very attractive manner.

20 An additional object of the invention is to provide a device having a number of slides for carrying the goods which may be pulled from the frame at will to more readily reach the articles.

25 Still another object is to provide a device, the frame of which is vertically adjustable so that the slides may be disposed in various inclined positions.

With these and other objects in view the 30 invention resides in the novel features of construction which will be hereinafter more particularly described and claimed.

In the accompanying drawing wherein similar reference characters designate like 35 parts throughout the several views,

Figure 1 is a side elevation of a portion of a display rack constructed in accordance with my invention;

Fig. 2 is a horizontal section taken on the 40 plane of the line 2—2 of Fig. 1;

Fig. 3 is a side elevation of one end of one of the slides, the yokes connected thereto being in section;

Fig. 4 is a horizontal section on the plane 45 of the line 4—4 of Fig. 3;

Fig. 5 is a vertical section on the plane of the line 5—5 of Fig. 3; and

Fig. 6 is a vertical section taken on the line 6—6 of Fig. 1.

50 This improved display rack may be enclosed in a casing or situated in a suitable position without the casing, as shown in the drawing. The rack comprises broadly a frame of any desired height in which is placed a number of vertically spaced goods carrying slides upon which the articles to

be vended are disposed. The frame is formed of a pair of vertical supports 1 of any desired length which are preferably placed adjacent the wall W, and an additional pair of upright supports 2, said last named supports preferably being in two parts so that their length may be increased or decreased. Each of the supports 2 has a foot portion 2^a which carries an inwardly extending threaded stud 3, and a main portion 2^b which is vertically and longitudinally slotted as shown at 4 to receive the stud 3, a wing nut 5 being disposed on said stud to clamp the main portion 2^b to the foot portion 2^a so that the parts may be held in adjusted positions.

These supports 1 and 2 may be secured to the floor by any preferred means and are held in spaced apart relation by a plurality of vertically spaced guide bars 6, two sets of which are provided, one connecting one each of the supports 1 and 2, while the other set connects the other pair of supports. Each of the guide bars 6 adjacent one end has a combination bearing and spacing block 7 secured thereto on its outer face. It might be here mentioned that the guide bars are preferably rectangular in cross section and have their widest sides disposed vertically. From each of the supports 1 at vertically spaced points thereon, pivot studs 8 project and are disposed in the bearing blocks 7, thus pivotally attaching the guide bars 6 thereto and also spacing them therefrom. The opposite ends of the guide bars 6 are pivotally connected to the main portions 2^b of the supports 2 by any preferred means.

These guide bars 6 are designed to support the goods carrying slides 9, one of which is provided for each pair of bars 6. Each slide 9 is substantially U-shaped in plan view and has its arms 10 disposed for slidable engagement with the inner faces of the guide bars 6 and of a length substantially equal to that of said bars. Upon each of the arms 10 is secured a pair of substantially U-shaped yokes 11 and 12, the arms of which engage the upper and lower edges of said arms and the bars 6, fingers 13 being extended from the ends of each of said arms of the yokes into engagement with the outer faces of the bars 6 so that said slides will be effectively held in engagement with said guide bars. It will be noted from Fig. 5 that the fingers 13 overlie the outer face of

each of the guide bars 6 only a slight distance, and that the spacing blocks 7 are relatively narrow so that the slides may readily move outward without the fingers 13 engaging either the supports 1 or the spacing blocks 7. Since the guide bars 6 are not spaced from the supports 2, these fingers 13 will engage said supports when the slides have been drawn outwardly to their fullest extent, thus providing a very simple arrangement for limiting the outward movement thereof.

In the upper edges of each of the guide bars 6 is formed a plurality of substantially V-shaped seats 14 in any of which ribs 15 also V-shaped which are formed on the yokes 11, are designed to be disposed. When it is desired to pull one of the slides outwardly, the same is lifted slightly so that the ribs 15 on the yokes 11 will be raised out of the notches 14, said ribs riding on the upper edge of each guide bar until the desired position is reached by the slide, whereupon it is allowed to move downward into its normal position with the ribs 15 engaging appropriate seats 14. This construction holds the slide in its adjusted position until the ribs are manually disengaged from the seats 14, the rear wall of said seat preferably being inclined upwardly and rearwardly so that said ribs will readily slide out of the same when it is desired to push the slide into its retracted position.

While I have illustrated each of the slides formed substantially U-shaped, it is obvious that if desired the same may be formed with a solid bottom or with any other means, depending upon the goods which are desired to be stored or displayed. In the present instance I have formed each of the arms 10 with a plurality of bearing sockets 16 to receive trunnions 17 which project from the opposite ends of material carrying members 18, the latter being either flat or cylindrical as preferred. Upon these members 18 goods such as ribbons and various kinds of clothes may be wound for the purpose of storing the same. The sockets 16 are preferably open so that the members 18 with the material carried thereby may be lifted from the slides at will.

When a customer desires to purchase a particular kind of fabric on any one of the slides 9, the front end of the frame is preferably lowered by adjusting the supports 2 so as to dispose the slides at an angle to the floor, thus greatly facilitating the removal of any particular slide. After the forward

end of the frame has been lowered, the proper slide is drawn outward until the desired cloth is readily accessible. After the purchase has been made the slide may be pushed into the frame and the same adjusted vertically or allowed to remain in its former position as most convenient.

I claim:

1. In a display rack of the class described, a guide bar having a plurality of seats in its upper edge, a slide movable on said bar, a U-shaped yoke embracing said slide and bar, said yoke being secured to said slide and movable on said bar, and a rib on the yoke engaging any one of said seats to hold the slide in adjusted position.

2. In a display rack of the class described, an upright support, a guide bar attached thereto, a spacing block interposed between said bar and support, an additional upright support having said bar attached thereto, a slide movable on said bar, a yoke secured to said slide and embracing said bar, said yoke and the last mentioned support coacting to limit the outward movement of said slide, and means for holding said slide in adjusted position.

3. In a display rack of the class described, an upright support, a guide bar having a plurality of seats therein, a spacing block carried by the bar, a pivot extending from said support into said spacing block, an additional upright support having said bar pivoted thereto, means for vertically adjusting said last mentioned support, a slide in engagement with the guide bar, a yoke secured to said slide and embracing said bar, and a rib on the yoke to engage any one of said seats to hold the slide in adjusted position.

4. In a display rack of the class described, a pair of guide bars, each having seats therein, means for supporting the same, a substantially U-shaped slide having its arms engaging said bars, yokes secured to the arms of said slide and embracing said bars, ribs on the yokes to engage any of said seats, and a plurality of material supports having trunnions extending from their ends, the arms of said slide having bearing sockets to receive said trunnions.

In testimony whereof I have hereunto set my hand in presence of two subscribing witnesses.

CARL W. CARLSON.
